US00D543934S

(12) **United States Design Patent** (10) **Patent No.:** **US D543,934 S**
(45) **Date of Patent:** **** Jun. 5, 2007**

(54) **BATTERY CHARGER**

(75) Inventors: **Donwoong Kang**, Camillus, NY (US); **Scott W. Osiecki**, Skaneateles, NY (US); **Robert S. Englert**, Syracuse, NY (US); **Garth R. Gibby**, Syracuse, NY (US)

(73) Assignee: **Eveready Battery Company, Inc.**, St. Louis, MO (US)

(**) Term: **14 Years**

(21) Appl. No.: **29/251,577**

(22) Filed: **Jan. 10, 2006**

(51) **LOC (8) Cl.** **13-02**

(52) **U.S. Cl.** **D13/107**

(58) **Field of Classification Search** D13/107-110, D13/118-119, 184; D14/251, 253, 432, 434; 320/107-115; 455/573

See application file for complete search history.

(57) **CLAIM**

The ornamental design for a battery charger, as shown and described.

DESCRIPTION

FIG. 1 is a front perspective view of a battery charger showing our new design;

FIG. 2 is a rear perspective view thereof;

FIG. 3 is a front plan view thereof;

FIG. 4 is a rear plan view thereof;

FIG. 5 is a top elevational view thereof;

FIG. 6 is a bottom elevational view thereof;

FIG. 7 is a first side elevational view thereof; and,

FIG. 8 is a second side elevational view thereof.

The broken lines shown in FIGS. 1, 2, 3, 4, 5, 7, and 8 are included for the purpose of illustrating environmental elements only and form no part of the claimed invention.
